UNITED STATES PATENT OFFICE

WILLIAM H. BUTLER, OF NEW YORK, N. Y.

DESIGN FOR A PLEASURE CAR

Application filed April 21, 1932. Serial No. 43,557. Term of patent 7 years.

To all whom it may concern:

Be it known that I, WILLIAM H. BUTLER, a citizen of the United States, residing at New York, in the county of New York and State of New York, have invented a new, original, and ornamental Design for Pleasure Cars, of which the following is a specification, reference being had to the accompanying drawings forming part thereof.

Fig. 1 is a side elevation of a pleasure car,

Fig. 2 is a similar view of the same pleasure car with the front curtain pulled down and the sliding doors closed.

Fig. 3 is a view similar to Fig. 2 except that the side curtains are also in place.

And Fig. 4 is a front elevation of the pleasure car as shown in Fig. 3.

I claim the ornamental design for a pleasure car, as shown and described.

WILLIAM H. BUTLER.
